UNITED STATES PATENT OFFICE.

DAVID B. WESTON, OF SHARON, MASSACHUSETTS.

CENTRIFUGAL SEPARATOR.

1,279,056.

Specification of Letters Patent. Patented Sept. 17, 1918.

Application filed November 14, 1912. Serial No. 731,232.

To all whom it may concern:

Be it known that I, DAVID B. WESTON, citizen of the United States, and resident of Sharon, county of Norfolk, Massachusetts, have invented certain new and useful Improvements in Centrifugal Separators, of which the following is a specification.

This invention relates to centrifugal separators and is intended to provide a simple and effective machine for separating from the raw liquor, such as cane juice or sludge, the heavier solid content from the lighter liquid constituent by a process that is carried on without interruption until the separated solid content accumulates sufficiently to practically fill the operative part of the centrifugal receptacle. Instead of separating separate charges which are successively treated in the machine, the liquid to be treated is supplied without interruption, and after clarification escapes out of the top of the centrifugal receptacle. Hence, a very large body of liquid in comparison with the cubical capacity of the receptacle may be treated before it is necessary to stop the operation in order to discharge the accumulated solid content. An additional object is to secure also the separation of any lighter than liquid constituent if the material to be treated contains such constituent.

To this end the invention consists generally of a centrifugal receptacle whose top and bottom members are provided with interior or central openings for the introduction and outflow of liquid while the machine is operating and for the discharge of the solid separated content through the bottom when the machine is at rest, combined with means so arranged in relation to the liquid outlet as to prevent the escape of unclarified liquid, before the solid matter has been separated therefrom. A further feature of the invention resides in the provision made for drawing off any lighter than liquid ingredient that the material to be treated may contain.

Such a machine is especially well adapted to clearing the cane juice in sugar mills, of the mud and dirt, and at the same time of the light fibrous particles of cane which can be recovered separately from the dirt for further treatment, such as the extraction of its wax content.

In the drawings, Figure 1 is a vertical

cross-section showing the preferred mode of embodying the principles of this invention; and

Fig. 2 is a diagrammatic plan view illustrating the arrangement of the radial wings and the deflecting plate.

60

According to the form of my invention illustrated, I employ an outside curb or casting *a* which surrounds the rotary basket *c*, which is rotatably suspended by means of the gyratory shaft *b* driven in any suitable 65 manner.

The circumferential or outer portion of the receptacle *c* is subdivided into pockets or compartments by means of a series of radial wings *c*² extending from the outer 70 wall inward part way to the center. The central portion of the basket is left clear, except for the presence of the suspension shaft *b*. The central portion of its bottom is provided with an aperture normally closed 75 by disk-like plate or gate *c'*. Above this gate is mounted a frusto-conical shield *d*, whose lower edge is located slightly above the bottom or floor of the receptacle to leave sufficient clearance for the outflow of the 80 liquid to be treated, into the several pockets. The shield *d* is open at its top so as to admit the lower end of a supply pipe *g*, which is supported by two hinged joints at *g'* and at *g*², in order that it may be folded up to 85 swing clear of the machine. By means of a handle or bar *d'*, the shield and its attached gate *c'* can be raised to allow the solid separated material to be discharged through the bottom port.

90

In order to have the liquid to be treated flow as nearly as possible in a straight vertical line in its passage through the receptacle, I provide an annular deflector *c*⁵, which is arranged adjacent to the lower 95 edge of the shield *d*, so as to deflect the liquid toward the periphery of the receptacle before the liquid begins to flow upward.

In the upper part of the receptacle a slight distance below its top wall *c*³, I secure an 100 annular and preferably inclined baffle plate *f* which extends around the receptacle with its inner edge projecting somewhat beyond the inner edge of the top wall *c*³, and whose outer edge terminates at a substantial distance away from the periphery of the receptacle, so as to leave a wide space or annular 105 channel for the flow of the liquid between

the baffle plate and the top wall of the receptacle, and to conduct the clear liquid to the inner edge of the top wall over which it flows to the space or chamber surrounding the receptacle.

For convenience I may use a flanged deflector ring o , whose depending vertical flange is located adjacent to the inner edge of the baffle plate f , which is mounted to leave an annular clearance space above the top wall c^3 of the receptacle, in order to guide the liquid into its chamber and prevent it from flowing or splashing over the inner edge of the diaphragm a^2 . In many cases, however, this deflecting ring will not be needed.

The liquid to be treated flows through the supply pipe g to the interior of the shield d , passes out underneath the bottom thereof toward the said wall of the receptacle c and partakes of the rotary motion of the receptacle which causes the wall of liquid to build up under the action of centrifugal force along the peripheral wall of the basket. In this position the heavy dirt or mud content of the liquid tends to build up next the cylindrical wall, while the light fibrous material tends to float on the inner surface of the wall of liquid. Fresh liquid continues to flow in until the thickness of the annular wall of the liquid is sufficiently great to allow it to begin to flow over the edge of the large opening in the top wall c^3 . At the time this action takes place the light fibrous material accumulated on the inner surface of the vertical wall of liquid extends downward beneath the baffle plate f , which acts, therefore, as a sort of skimmer to hold back the light material, while allowing the liquid to flow over the top of the baffle plate and out of the receptacle or basket. It will be noted that the inner edge of the baffle plate f projects inward slightly beyond the corresponding edge of the top wall c^3 , so that the liquid will begin to discharge through the top of the basket before it can flow around the inner edge of the baffle plate f . This operation continues until the deposit of solid matter next the cylindrical wall of the basket c has accumulated to such a thickness or depth, as to interfere with the normal operation, at which time the supply is cut off and the machine may be stopped and the solid content discharged through the central opening in the bottom.

When, however, it is desired to keep the lighter material separate from the heavier solid material, the operator will simply reduce the speed of the machine, without stopping it, and then by opening the valves h , which control the outlet pipes h' , allow the light fibrous material to escape through the outlets h into the upper chamber formed in the curb above the diaphragm a^2 , and the light fibrous material is sufficiently impreg-

nated with moisture to allow it to flow readily through these passages under the pressure caused by the centrifugal force due to the rotation of the machine.

As it is desired to open the valves h without stopping the machine, a cam-like device i may be supported in proper position from the top wall of the curb a , which can be lowered by a screw and hand-wheel i' so as to bring the cam member i into operative contact or engagement with the valve cocks h to throw them to open position while the machine is running. The light fibrous content having thus been drawn off into the space above the diaphragm a^2 , the machine may be stopped in order to allow the gate c' to be raised, so that the operator can scoop down the heavy solid content and allow it to discharge through the bottom of the basket.

The upper and lower annular members or walls form in connection with the peripheral wall the means for retaining the solid material extracted from the liquid fed into the receptacle. The baffle plate f being located to overlap the outlet opening, makes it impossible for unclarified liquid, from which the solid has not been extracted, to escape around the inside edge of the top c^3 , and also acts to retain the lighter than liquid ingredient which accumulates on the inside wall of the receptacle beneath the baffle plate, until it is drawn off through the offtake pipes h' .

This arrangement permits the continuous operation of the machine until the heavier solid matter has accumulated to such an extent as may require its discharge. In that case the machine is stopped, the bottom valve plate c' is raised and suspended out of the way, giving the attendant an opportunity to loosen the solid material and allow it to fall by gravity through the central discharge opening in the bottom. The cycle of operations may then be resumed by starting the machine and restoring the feed pipe to proper feed position after the valve has been lowered to operative position.

While the valve is useful under some conditions, it is not to be understood that it is by any means indispensable for various kinds of work.

What I claim is:

1. In a centrifugal separator the combination of the rotary centrifugal receptacle having annular top and bottom members projecting inward from its peripheral wall and providing central openings, a series of radial wings arranged in the peripheral portion of the receptacle between the annular top and bottom members, an annular baffle plate arranged adjacent to the inside edge of the top member and projecting both inwardly and outwardly beyond said edge, and a valve plate for closing the opening in the bottom member and removable from its seat in order

to permit the discharge of the solid matter through said opening, substantially as described.

2. The combination of the centrifugal receptacle having top and bottom annular walls leaving central openings, means for introducing the liquid to be treated into the lower peripheral portion of said receptacle, an annular baffle plate arranged in the upper part of said receptacle to overlap the edge of the outlet in the top, a surrounding casing comprising two draw-off compartments, a deflecting hood arranged in the outlet opening of the receptacle to discharge the clarified liquid into one compartment, one or more offtake pipes whose inlet ends communicate with the zone below said baffle plate and whose outlet ends discharge into the other draw-off compartment and means for opening and closing said offtake pipes, substantially as described.

3. A centrifugal receptacle for a separator comprising the peripheral wall, upper and lower members secured thereto and projecting inwardly therefrom so as to leave central openings, a suspension spider arranged in the lower opening to form a supporting means for the receptacle to connect it with a rotary shaft, upper and lower annular baffle plates located within said receptacle, 25 a deflector hood mounted on top of said receptacle and projecting inside the annular top, and a series of vertical wings or vanes arranged in the peripheral portion of said receptacle, substantially as described. 30 35

In witness whereof, I have subscribed the above specification.

DAVID B. WESTON.
